United States Patent Office.

JOHN H. CUMMINGS, OF BOSTON, MASSACHUSETTS.

Design No. 2,583, dated February 19, 1867.

DESIGN FOR A MONOGRAM.

The Schedule referred to in these Letters Patent and making part of the same.

TO ALL WHOM IT MAY CONCERN:

Be it known that I, JOHN H. CUMMINGS, of Boston, in the county of Suffolk, and State of Massachusetts, have invented or produced a new and ornamental Design for a Monogram of the letters U. S., as an abbreviation for the words "United States," the design being for the faces of badges, pins, army plates, buttons, &c.; and I do hereby declare that the following is a full and clear description of my design, which is shown in the accompanying drawings, forming part of this specification.

The design is intended chiefly as an association of the letters U. S. with army or navy service, and for this purpose the outline of the letter U is in the form of a shield, the end of the shield being made by the upper bars of the letter U and the upper line of S.

Generally the design is to be cut out of plate metal by dies, the action of which shall leave the part of S lapping over the lines of U in relief above U.

I claim the design for a monogram of the letters U. S. in the form of a shield, as shown in the drawings.

JOHN H. CUMMINGS.
